UNITED STATES PATENT OFFICE.

CHARLES B. SAMPLE, OF TERLTON, OKLAHOMA TERRITORY.

COTTON BLENDING AND CLEANING APPARATUS.

SPECIFICATION forming part of Letters Patent No. 763,798, dated June 28, 1904.

Application filed March 1, 1904. Serial No. 195,982. (No model.)

To all whom it may concern:

Be it known that I, CHARLES B. SAMPLE, a citizen of the United States, residing at Terlton, in the county of Pawnee, Oklahoma Territory, have invented new and useful Improvements in Cotton Blending and Cleaning Apparatus, of which the following is a specification.

My invention relates to new and useful improvements in cotton blending and cleaning apparatus adapted to be used in connection with cotton-gins or otherwise; and its object is to provide an apparatus which will remove from seed-cotton all foreign substances which may be commingled therewith, thus making the cotton clean and subsequently white and preserving the original luster of the cotton, thereby saving the usual reduction in price on account of the presence in the cotton of dust, dirt, mold, and rubbish, which causes the cotton on the market to appear dark and grade low.

Another object is to keep the cotton-ginning machinery clean of dirt and dust and to discharge the dust, rubbish, &c., into any suitable receptacle provided therefor and to automatically feed the clean cotton to the gin-stand.

A further object is to provide means whereby the cotton may be carried by suction through the cleaning apparatus.

Another object is to provide novel means for separating and mixing the cotton, so as to blend any stained cotton with the white material, so as to render the stained stock invisible to the eye after the ginning operation, thereby saving the usual reduction in the price upon the mass because of the discolored cotton.

The invention consists in the novel construction and combination of parts hereinafter more fully described and claimed, and illustrated in the accompanying drawings, showing the preferred form of my invention, and in which—

Figure 1 is a vertical section. Fig. 2 is a section on line 2 2, Fig. 1. Fig. 3 is a section on line 3 3, Fig. 1. Fig. 4 is a perspective view of a guide plate or tooth. Fig. 5 is a horizontal section through the feed-wheel.

Referring to the figures by numerals of reference, 1 is a frame of any suitable construction having a casing 2 supported thereon, the bottom of which forms a hopper 3, having an outlet-pipe 4. Arranged within the casing is a frusto-conical jacket 6, which extends partly over the hopper 3 and communicates at its upper end with an air-tight hood 7. A shaft 8 is journaled within the frame 1 and extends through the center of the casing 2 and jacket 6 and also through the hood 7. This shaft is provided with a pulley 9 or other suitable means, whereby it may be rotated by any suitable power. Within the hood 7 is a feed-wheel 10, which is secured on the shaft 8 and is adapted to be rotated thereby. This wheel is formed of a series of laterally-extending wedge-shaped partitions 11, the upper ends of which are covered by a screen 12, and is incased with a band 30^a around the outer extremity 70 of said partitions and screen, as shown in Fig. 1. This wheel is eccentrically arranged within the hood 7 and is supported by the shaft 8 above a partition 13, which projects into the hood and has a tight-fitting cover 13^a and a downwardly-extending flange 14. This flange and one of the sides of the hood 7 form a hopper 15, the outlet of which is in vertical alinement with the chamber formed between the jacket 6 and a hollow frusto-conical roll 16, secured 80 to the shaft 8 and concentric with the jacket 6. Partitions 17 connect the shaft with the roll, and both ends of the roll are closed by disks 16^a and 16^b, the upper end being provided with an air-inlet 5. The lower end of the roll 16 and fan-blades 27, secured to said end, are revolvably mounted above and adjacent the bottom 18 of the jacket. A circular tube 20 incloses the aperture 5 and extends upward from the roll 16 to a point above the lower edge of flange 14, and this circular tube forms an inlet-tube through which air may be admitted to the roll 16. Fan-blades 21 extend laterally from the tube 20 and are provided at their outer ends with inclined teeth 95 or projections 22. The tube 20 is connected to the shaft 8 by means of arms 23, interposed therebetween. Long angular teeth 24 are struck outward from the roll 16, and angular apertures 24^a are thus formed in the roll for 100

the escape of air entering the inlet 5 and forced outward by the rapidly-rotating fan-blades 17. A number of apertures 25 are formed in the jacket 6. An outlet-tube 26 extends 5 from one side of the jacket 6, at the bottom thereof, and extending from the shaft 8 in horizontal alinement with this outlet-tube is the series of fan-blades 27, before referred to. The outlet-tube in cross-section is preferably 10 of the form illustrated in Fig. 3, and it will thus be seen that when the blades 27 are rotated in the direction of the arrow in Fig. 3 any material in the paths thereof will be thrown and blown outward into the tube 26. 15 This tube communicates with a feed-tube 28, arranged at the upper ends of a gin-feed 29, and the outer end of the tube is normally open. A diagonally-arranged screen 31 extends transversely across the tube 28, the inclination being such as to direct outward any material brought into contact therewith from the tube 26.

A suction-tube 34 opens into the partition 13 at a point below the wheel 10 and in vertical alinement with the end of a suction-tube 33, and this tube 34 is preferably provided with a vertical portion 34^a, at the base of which is arranged a receptacle 35 for the reception of stones and other heavy foreign 20 particles. This receptacle is preferably normally closed at the bottom by means of a cap 36.

The teeth 22 move beneath guide-plates 22^a, secured to the inner face of the jacket 6 at its 25 upper end, and force the cotton into the space between the roll 16 and the jacket 6. The seed-cotton is sucked into the cleaning apparatus through the pipe 34, and in passing the receptacle 35 all heavy particles carried thereby—such as stones, &c.—will fall by gravity thereinto and can subsequently be removed by first detaching the cap 36. The cotton is drawn upward into the feed-wheel 10 by the suction of air through tube 33, and its upward 30 movement is stopped by the screen 12. As the wheel 10, together with the fans 21, 27, and 17 and the roll 16, are rapidly rotated with the shaft 8, it will be understood that the cotton will be quickly carried into the hopper 15 by the wheel 10 and will drop therethrough by gravity, assisted by air which is drawn into the hopper 15 through tube 10^a by fan-blades 21. When the cotton comes in contact with the blades 21 and the inclined teeth 22 thereon, it will be forced under the guide-plates 22^a upon the jacket 6. The air from tube 10^a and a portion of the dirt and dust contained in the cotton will be blown out by centrifugal force through apertures 25 in jacket 6, and 40 the cotton will be forced downward by the rotation of the roll 16 and teeth 22 and will be forced by inclined guide-plates 22^a into the space between the jacket 6 and the roll 16.

Air enters the roll through the inlet 5 and 45 is forced outward by centrifugal force from

the rapidly-rotating fan-blades 17, which revolve with the roll. This air as it passes through the apertures 24^a blows the cotton which is between the roll and jacket firmly into the apertures 25 in the jacket 6, and it is rapidly thrown from these apertures by the teeth on the roll 16. The cotton is also thrown by centrifugal force against the apertured jacket with such force as to separate loose particles of foreign material from the cotton and force them through the apertures. The cotton is thus thoroughly separated, each seed from the others, with its adhering lint, and the air passes through it and carries all dust and rubbish, mildew, or mold through the apertures 25 into the casing 2, from which it is blown outward through the pipe 4. The cotton is carried downward and around the jacket 6 in a spiral course as it is alternately blown into apertures 25 and thrown from them by 50 teeth 24 as they rotate with the roll, and it is blown and thrown against the inner inclined sides of the hollow frusto-conical jacket 6, and this spiral downward movement of the cotton is assisted by the air discharged through the 55 apertures in the roll and which is directed downward by the inclined teeth on the roll. When the cotton reaches the bottom of the compartment formed between the jacket and the roll, it is forced under plates 22^a at the 60 bottom of the jacket 6 and is discharged therefrom by the teeth 22 on the fan-blades 27, which throw and blow it into the tube 26 and against the screen 31, and it drops therefrom into the gin-feed 29. During the downward 65 course of the cotton between the perforate jacket 6 and the roll 16 it is continuously subjected to the cleaning effect of the air-blast or air under pressure delivered thereagainst centrifugally with respect to the shaft 8 and the 70 blades 17 thereon, and thereby forced outwardly against the jacket and over the openings 25, the latter being cleared regularly by the downward feed action of the teeth 24, as before set forth; but the retention of the cotton against the jacket 6 over a portion at least of the openings 25 is materially beneficial in the cleaning operation, in view of the fact that the cotton is held in one position for a greater 75 length of time and more thoroughly subjected to the cleaning influence of the air forced outwardly thereagainst. During the time that the cotton is held against the jacket 6 over the openings in the latter a resistance is temporarily set up to the escape of the air through 80 said openings in an outward direction, and by this operation the air is more fully utilized in cleaning the cotton by reason of being forced to some extent therethrough. The most effective cleaning operation ensues between the planes of the plates or disks 16^a and 16^b, and as the outwardly-forced or centrifugally-applied air without obstruction would have the 85 tendency to pass out or escape in the direction of least resistance it would pass downwardly 90

toward the bottom 18 of the jacket 6, and a large part thereof would escape into the discharge-tube or outlet 28. This operation would take place in view of the closure of the 5 openings 25 by the cotton forced thereagainst, and the cotton would not be as thoroughly cleaned and blended. To obstruct this downward movement and escape of the air, the fan-blades 27, providing a pneumatic resistance, 10 are located in the bottom of the jacket under the lower disk or plate 16^b, and though this lower pneumatic resistance means does not interfere with the mechanical feed of the cotton toward the discharge it does operate to 15 counteract the loss of any of the forceful effect of the air thrown outwardly through the roll or toothed device and jacket, especially in view of the fact that each of the fans or air-pressure-creating devices has independent air-current-feeding means. In other 20 words, the strata of air-pressure created by the fan arranged externally of the enlarged extremity of the roll is sufficient in resistance to hold the air-pressure forcing the cotton 25 outwardly against the jacket within the cleaning-space between the planes of the disks or plates 16^a and 16^b. The upper fan, or that within the reduced extremity of the roll 16, also forces air outwardly against the cotton 30 at the point where the latter enters the space between the roll and jacket to perform an initial cleaning step, and this fan also operates as a resistance means to prevent the escape of the air thrown outwardly by the intermediate 35 fan comprising the blades 17 through the feed end of the machine and obstructs any tendency to retardation of the feed of the cotton by the means heretofore explained. Thus it will be seen that a pneumatic resistance 40 means is located at opposite extremities of the main cleaning portion of the space between the roll and jacket where the most effective cleaning and blending of the cotton takes place. It will be observed that the resistance or obstruction of the fan-blades 27 45 to the loss or escape of the pressure of the blades 17 is materially assisted by contracting the outlet 26, such contraction or restriction of this outlet causing the air-pressure of the 50 fan comprising the blades 27 to be thrown upwardly. One or more gin-feeds may be thus filled, for when the cotton fills up to the screen 31 in the farthestmost connected gin-feed the air-current is thereby retarded and 55 the cotton falls nearer to the fans 27 until the cotton against the screen is worked down. The cotton is then blown against the screen as before.

By providing a jacket of frusto-conical 60 form the passage of the cotton toward the outlet 26 is facilitated for the reason that each time the cotton is drawn out of the apertures in the jacket by the teeth on roll 16 it is driven back against the jacket, but at a point nearer 65 the discharge end thereof.

It will be understood that in addition to cleaning cotton the apparatus can also be used for commingling stained cotton with white cotton, so as to prevent the loss which is occasioned by the reduced price given for dis- 70 colored stock.

The apparatus may also be employed for drying the cotton which is too damp for ginning. The apparatus can be disconnected from the cotton-gin and used for blending 75 and cleaning seed-cotton by first removing cover 18^a and feed-wheel 10. Cotton can then be placed in the hopper and will be operated upon by the teeth 22 and plates 22^a, as hereinbefore described. An air-inlet tube 10^a is 80 so arranged within the hood 7 as to permit air to pass therethrough to a point adjacent the center of the feed-wheel 10 and to fans 21, and an air-inlet tube 27^a is preferably arranged in the bottom 18 of jacket 6, so as to supply 85 air to the center of the fan 27. This air is thrown outward by the fans for the purposes hereinbefore set forth.

In the foregoing description I have shown the preferred form of my invention; but I do 90 not limit myself thereto, as I am aware that modifications may be made therein without departing from the spirit or sacrificing any of the advantages thereof, and I therefore reserve the right to make such changes as fairly 95 fall within the scope of my invention.

Having thus described the invention, what is claimed as new is—

1. In a blending and cleaning mechanism, 100 the combination of a cleaning device, a hopper, a revoluble feed-wheel in said hopper and comprising laterally-extending wings, a screen upon the wings, and means for pneumatically supplying material to said wheel.

2. In a blending and cleaning mechanism, 105 the combination of a cleaning device, a hopper, a revoluble shaft, wings extending laterally therefrom, a screen upon the wings, a band around the screen and wings, said screen, wings and band forming a feed-wheel for the 110 hopper, a tube for supplying material pneumatically to the bottom of the wheel, and a receptacle communicating with the tube.

3. In a blending and cleaning mechanism, 115 the combination with a cleaning device, a hopper, a revoluble shaft, blades extending therefrom, a screen upon the blades, a band encircling the screen and blades, said screen, blades and band forming a feed-wheel for the hopper, a pneumatic feed-tube opening below the 120 feed-wheel, a depending receptacle communicating with said tube, and a suction-tube above the wheel.

4. In an apparatus of the character described, the combination with a casing, and a 125 hopper forming the bottom thereof; of a jacket within the casing having apertures therein, guide-plates on the jacket, a hood to the jacket, pneumatic feed mechanism within and communicating with the hood, a hollow 130

1. inclosed roll revolubly mounted within the jacket and having apertures therein, teeth upon the roll adjacent the apertures therein, a tube extending upward from the roll, and laterally-extending fan-blades upon the shaft and adjacent an outlet in the jacket.
2. In an apparatus of the character described, the combination with a casing having a hopper-shaped bottom, and an outlet therefrom, of a frusto-conical jacket within the casing and forming a space between the casing and the jacket, said jacket having a bottom thereunder and apertures therein, a hood upon the jacket, a revoluble feed-wheel within the hood, an inlet-tube within and extending from the casing, fan-blades upon said tube, teeth upon the blades, a revoluble frusto-conical roll within the jacket and having apertures therein, a space being formed between the roll and jacket, teeth upon the roll and adjacent the apertures therein, plates upon the jacket adjacent the apertures therein, fans within the roll, a hopper within the hood, and fan-blades extending from the shaft and within the jacket and adjacent an outlet in the jacket.
3. In an apparatus of the character described, the combination with a casing having a hopper-shaped bottom and an outlet therefrom, of a jacket within the casing and forming an opening between the casing and the jacket, a roll within said jacket, a bottom to the jacket and apertures in the jacket, a hood upon the jacket; a revoluble feed-wheel therein, means for directing material from said wheel to a point between the jacket and roll, and fan-blades upon the shaft and adjacent an outlet from the jacket.
4. In an apparatus of the character described, the combination with a casing, and a hopper thereunder forming a bottom therefor, said hopper having an outlet; of an apertured jacket within the casing and forming an opening between the casing and the jacket, a revoluble shaft within the jacket, an apertured roll upon the shaft and within the jacket, plates upon the jacket and teeth upon the roll and adjacent the perforations, an inlet-tube extending upward from the roll, wings upon said tube, teeth upon said wings and adjacent the perforations in said jacket, a hood upon the jacket, blades within the hood and extending from the shaft, a screen upon the blades, a band around the screen and blades, said screen, band and blades forming a feed-wheel, a hopper within the hood, a pneumatic inlet-pipe opening into the hood below the wheel, a pneumatic outlet-tube extending from the hood and above the wheel, an inlet-pipe opening into the hood adjacent the center of said wheel, an outlet-tube extending from an outlet in the jacket, material-retarding means in the tube, and fan-blades upon the shaft and adjacent said outlet.
5. In an apparatus of the character de-

scribed, the combination with a stationary jacket having apertures therein; of an apertured frusto-conical roll revolubly mounted within the jacket and partitions within the roll.

6. In a device of the character described, the combination with a hollow jacket having apertures therein and a bottom thereto, of a hollow frusto-conical apertured roll revolubly mounted within the jacket and having teeth thereon, and partitions within the roll and extending longitudinally thereof.

7. In an apparatus of the character described, the combination with a stationary hollow frusto-conical jacket having apertures therein and a bottom thereunder; of a hollow frusto-conical apertured roll revolubly mounted within the jacket and having its walls parallel with the walls of the jacket, and partitions within the roll and extending longitudinally thereof.

8. In an apparatus of the character described, the combination with a hollow frusto-conical jacket having apertures therein; of a hollow frusto-conical roll revolubly mounted within the jacket and having its walls parallel with the walls of said jacket, said roll having apertures therein, inclined teeth extending from the roll adjacent its apertures and having its ends closed, a tubular inlet opening upward from said roll, and partitions within the roll and extending longitudinally thereof.

9. In an apparatus of the character described, the combination with a hollow frusto-conical jacket having apertures therein and plates extending inward from the jacket; of a hollow frusto-conical roll revolubly mounted within the jacket and having apertures therein, fan-partitions secured within the roll and extending longitudinally thereof, inclined teeth extending from the roll adjacent the apertures, and a tubular inlet extending from the interior of said roll.

10. In an apparatus of the character described, the combination with a hollow frusto-conical jacket having guide-plates extending inwardly therefrom, and adjacent apertures therein, and a casing inclosing the jacket; of the hollow frusto-conical inclosed roll revolubly mounted within the jacket and having its walls parallel with the walls of the jacket, said roll having apertures therein, blades within the roll, inclined teeth extending from the roll and adjacent its apertures, a shaft within the roll and secured to the blades and roll and extending from the inclosed ends of said roll, a tube upon the shaft and extending into the roll, blades upon said tube, teeth upon the blades, means for conveying material to the blades and teeth, and to the space below said blades and between the jacket and roll, a fan upon the shaft in alinement with an outlet and below the opening, a tube to the outlet, and means for retarding said material within the tube.

14. In an apparatus of the character described, the combination with a jacket tapered upward from the lower end thereof and having apertures therein, and plates extending inwardly from the jacket; of an apertured tubular roll revolvably mounted within the jacket and having its walls parallel with the walls of the jacket, partitions within the cylinder, inclined teeth extending from the cylinder adjacent to the apertures therein, and a tubular inlet extending upward from said roll.
15. In an apparatus of the character described, the combination with a casing having an outlet, of an apertured jacket within the casing, an apertured toothed tubular roll revolvably mounted within the jacket, fan-partitions within the roll, a shaft within and extending from the roll, an inlet-tube upon the shaft and roll, fan-blades upon the tube, teeth upon the blades, means for conveying material to the blades and teeth, means for directing said material to a fan in alignment with the outlet, a tube extending from the outlet, and material-retarding means within the tube.
16. In an apparatus of the character described, the combination with a casing having a hopper-shaped bottom provided with an outlet; of a stationary apertured jacket within the casing and having a bottom thereto, a toothed apertured roll revolvably mounted within the jacket, an outlet-tube extending from the jacket, and fan-blades revolvble with the roll and adjacent the tube.
17. In an apparatus of the character described, the combination with a stationary casing having an outlet at one end, and a hopper at the other end; of a stationary apertured jacket within the casing and communicating with the hopper, said jacket having a bottom, a toothed apertured roll revolvably mounted within the jacket, an air-inlet tube opening into the roll, partitions within said roll, and means at one end of the roll for expelling material from the jacket.
18. In an apparatus of the character described, the combination with a stationary casing having an outlet at one end, and a hopper at its other end; of an apertured frusto-conical jacket within the casing and adapted to receive material from the hopper, an outlet-tube extending from the jacket, a hollow frusto-conical roll revolvably mounted within the jacket and having its walls parallel with the walls of the jacket, teeth extending from the roll adjacent apertures therein, longitudinally-extending partitions within the roll, an air-inlet tube opening into the roll, and material-expelling means revolvble with the roll and adjacent the outlet-tube.
19. In a device of the character described, the combination with a casing having a bottom provided with an outlet; of a stationary jacket within the casing and having apertures therein, guide-plates on the jacket adjacent its feed end, a revoluble toothed device mounted within the jacket, transversely-extending disks at the ends of the toothed device, and means for forcing air outwardly through the apertures in the jacket.
20. In an apparatus of the character described, the combination with a casing; of a jacket within the casing and having apertures therein, guide-plates on the jacket, a rotary toothed device within the jacket, means for feeding material to one end thereof, disks at opposite ends of the toothed device, laterally-extending fan-blades below and revolvble with the toothed device and adjacent an outlet in the jacket, and means for supplying air to said blades.
21. In an apparatus of the character described, the combination with a casing having an outlet; of an apertured jacket within the casing, a revoluble toothed device within the jacket for driving material against the jacket and subsequently tearing the same therefrom, and fans adjacent the ends of said device.
22. In a machine of the class set forth, a casing having a cleaned-material outlet, an apertured jacket within the casing, a revoluble toothed device within the jacket and forming a feed-space with the latter, an intermediate pneumatic means for forcing material outwardly against the jacket, and pneumatic counteracting means adjacent to one end of the toothed device for preventing the air-pressure of the intermediate pneumatic means from escaping through the outlet.
23. In a machine of the class set forth, an imperforate casing having outlet means, a perforate jacket within the casing, a tooth-carrying device in the jacket having openings therethrough and a closed end, a space being formed between the tooth-carrying device and jacket for the feed therethrough of material to be treated, a pneumatic means for forcing air outwardly through the tooth-carrying devices and jacket, and a counteracting pneumatic pressure means arranged adjacent to the closed end of the tooth-carrying device and operating to hold the air-pressure created by the said pneumatic means within certain confines in the space between the tooth-carrying device and jacket.
24. Devices having an intervening space between them for the passage of material to be cleaned and formed with openings therearound, one of said devices having feed-teeth, a pneumatic means for forcing air outwardly through both devices to cause the material cleaned to adhere to one of said devices, an air-pressure-creating means adjacent to the end of the device carrying the feed-teeth for obstructing the escape of the outwardly-thrown air-pressure of the first-named pneumatic means, and an imperforate casing surrounding the said devices and having an outlet, and another outlet communicating with the pneu-

matic means at the end of the tooth-carrying device.

25. Inclosed material-feeding devices having openings therethrough and a space between them, means for forcing air outwardly through said devices, and pneumatic means also inclosed and adjacent the end of one of said devices for obstructing the loss of the

pressure effect of the said means for forcing air outwardly. 10

In testimony whereof I affix my signature in presence of two witnesses.
